UNITED STATES PATENT OFFICE

103,356

DESIGN FOR A TRANSFORMER

Gerard McL. Cole, Chicago, Ill., assignor to General Transformer Corporation, Chicago, Ill., a corporation of Illinois

Application December 12, 1936, Serial No. 66,497

Term of patent 7 years

To all whom it may concern:

Be it known that I, Gerard McL. Cole, a citizen of the United States, residing at Chicago, in the county of Cook and State of Illinois, have invented a new, original, and ornamental Design for a Transformer, of which the following is a specification, reference being had to the accompanying drawing, forming part thereof,

Fig. 1 is a front elevation of a transformer embodying the invention;

Fig. 2 is a side elevation of the transformer; and
Fig. 3 is a plan view of the transformer.

I claim:

The ornamental design for a transformer, as shown,

GERARD McL. COLE.
